UNITED STATES PATENT OFFICE

JOHN H. McILVAINE, OF EVANSTON, ILLINOIS

AIR-CONTROL SHUTTER

Application filed January 31, 1930. Serial No. 424,920.

This invention relates to an air control shutter especially designed for use in connection with the centrifugal fan or blower of a liquid fuel burner, but, of course, adapted for use with other kinds of burners, regardless of the kind of fuel being used.

More specifically stated, the air control shutter of my invention is designed for use with a burner operating with a continuous but variable flame, from a low load flame to a high load flame through a number of intermediate heats sufficient to maintain the desired temperature in the home or other building being heated under all usual and ordinary conditions. This kind of operation, therefore, requires that oil and air be fed in proper proportions and in definite predetermined amounts for the different loads, a very small amount of air being required for the low load flame and the maximum amount for the high load flame and amounts in proportion for the intermediate loads. It is, therefore, the principal object of my invention to provide a shutter which enables the air adjustments for the different loads to be made easily and accurately, the adjustments for all loads from the low load flame through the intermediate loads to the high load flame being each made independently by the setting of closures on openings provided for the different loads whereby to produce the proper combustion throughout the range of heats and thus make for economy and efficiency.

The invention is illustrated in the accompanying drawing wherein—

Figure 1 is a side view of the blower showing the air control shutter of my invention applied thereto;

Fig. 2 is a section on the line 2—2 of Fig. 1;

Fig. 3 is a face view of the movable shutter plate removed from the blower and having none of the closures thereon for the different shutter openings; and

Fig. 4 is a similar view of the stationary shutter plate.

The same reference numerals are applied to corresponding parts throughout the views.

The air control shutter is shown mounted 50 on the housing 5 of a centrifugal fan or

blower that has an air delivery pipe 6 attached thereto and leading to the combustion chamber into which the oil to be burned is delivered. A constant speed motor, a portion of whose housing appears at 7, drives a pump to feed the oil at different rates according to the adjustment of an oil control valve in the oil feed line. The oil control valve is adjusted by means of a suitable thermostatic regulator and, as will presently appear, the air control shutter is arranged to be adjusted at the same time by the same means so as to supply the proper amount of air in proportion to the amount of oil delivered to the combustion chamber, for proper combustion. The blower housing 5 is suitably mounted on the motor housing 7 with the armature shaft 8 extending therein to drive the blower wheel 9, designed for the delivery of air under low pressure to the air delivery pipe 6 leading to the combustion chamber. On the inlet side of the blower housing is mounted a plate 10 enclosing the peripheral portions of the blades of the blower wheel and having a central air inlet opening 11. The shutter of my invention for controlling the air supply to the blower, and consequently to the combustion chamber, consists of a stationary shutter plate 12 bolted to the blower housing along with the plate 10, as indicated at 13, and a movable shutter plate 14, mounted to turn relative to the plate 12 on a bolt 15 passing through a center hole in the plate 12 and threaded in a central boss on the plate 14. A coiled compression spring 16 under the head of the bolt 15 acts through the latter to hold the plate 14 seated on the plate 12 so as to prevent leakage of air between the contacting surfaces.

The stationary shutter plate 12 has two diametrically opposed open quadrants 17 and 18 and intermediate closed quadrants 19 and 20. The movable shutter plate 14 has diametrically opposed closed quadrants 21 and 22, and intermediate open quadrants on the same radius as the open quadrants 17 and 18 of the stationary plate 12. The open quadrants in the movable shutter plate 14 are graduated in size, comprising openings 23, 24 and 25 at one side of the shutter plate and open-

ings 26, 27 and 28 at the opposite side, and each is adapted to be closed to a variable degree by a closure plate held in position on the movable shutter plate 14, as by means of screws 29, the said closure plates for the openings being numbered 30 to 35, inclusive. When the movable shutter plate 14 is in closed position, that is, with the two quadrants containing the openings 23 to 28, inclusive, superposed on the closed quadrants 19 and 20 of the stationary shutter plate, it is obvious that none of these openings will pass air to the blower inlet opening 11. Under these conditions the blower fan-wheel merely revolves in the housing and delivers no air to the combustion chamber except what is passed through two other openings 36 and 37, provided in the movable shutter plate 14 on a smaller radius than the other openings 23 to 28, hereinafter referred to as the low load inlet openings. These openings register with arcuate extensions 36' and 37' of the open quadrants 17 and 18 in the stationary shutter plate 12. Plates 38 and 39 are provided as closures for the openings 36 and 37, respectively.

In operation, the movable shutter plate 14 is in closed position when the handle 40 thereof is in engagement with a stop pin 41 projecting from the stationary shutter plate 12, and under these conditions the closure plates 38 and 39 are arranged to be adjusted over the openings 36 and 37 to positions where only the proper amount of air is allowed to enter for supporting combustion at low load. This is a very important adjustment because the admission of too much air at low load might result in the flame being extinguished. The control afforded by the closure plates on the openings is as accurate as need be and permits adjustment down to precisely the right amount of air, as distinguished from other means which have been provided in the past and which afforded only a comparatively coarse adjustment. After the air adjustment for the low load flame has been made the movable shutter plate 14 is turned one step at a time and adjustments of the closure plates 30 to 35 are made one at a time, the control valve in the oil feed line being opened wider and wider at each step by reason of a link connection 42 with an arm on the stem of said valve. The conditions peculiar to each installation, responsible for the fact that greater or less amounts of air may be required at various loads in proportion to the fuel feed in order to assure complete and proper combustion, are, therefore, met by the provision of an air control shutter made in accordance with my invention that permits of variation in the amount of air for every fuel feed to produce proper combustion. It will now be observed that the shutter openings 23, 24 and 25 are located diametrically opposite from the plates 33, 34 and 35, respectively, and that the openings 26, 27 and 28 are similarly positioned

with respect to the plates 30, 31 and 32. Thus, the opening 23 is first to have its closure plate 30 adjusted, then the opening 26 and then the opening 24 and so on, the openings being arranged to open in succession alternating from one series to the other. In each case the screws for the closure plate are loosened and the plate is slid over part of the opening to cut down the draft through the opening to the correct amount and is then locked in such position by the tightening of the screws. When the handle 40 comes into engagement with the stop pin 43 the shutter is in its high load position and all of the openings in the movable shutter plate are passing air for delivery through air intake opening 11 of the blower. In conclusion, it is to be noted that another link connection 44 is provided for the movable shutter plate; this is in the event that automatic control is desired, as for example, by means of a suitable thermostatic regulator having connection with the link shown.

It is believed the foregoing description conveys a clear understanding of all of the objects and advantages of my invention.

I claim:

1. In an air control shutter mechanism of the character described, the combination of a stationary part and a relatively movable shutter part movable from one limit position to another relative thereto, said stationary part having one or more air inlet openings, said movable part having a plurality of main air inlet openings arranged to be moved in succession into registration with the aforesaid openings by operation of the movable part, means for varying the size of said main air inlet openings, all of said main air inlet openings being out of register with the aforesaid openings when the movable part is in one limit position, the stationary part having a secondary air inlet opening, there being a secondary air inlet opening provided in the movable part arranged to register therewith when said movable part is in the limit position referred to, and means for varying the size of said last mentioned opening.

2. In an air control shutter mechanism of the character described, the combination of a stationary shutter part and a relatively rotatable shutter part arranged to turn from one limit position to another, the stationary part having diametrically opposed air inlet quadrants and the movable part having diametrically opposed closed quadrants arranged to cover the inlet quadrants when the rotatable part is in one limit position, the rotatable part having in diametrically opposed relation a plurality of air inlet openings arranged to be moved into registration with the air inlet quadrants in the turning of the rotatable part toward the other limit position, means for varying the size of said

openings, the stationary part having at least one of the air inlet quadrants provided with a cut-out portion constituting an extension of one part thereof and the rotatable part having a secondary air inlet opening registering therewith, and means for varying the size of said opening.

3. In an air control shutter mechanism of the character described, the combination of 10 a stationary shutter part, and a relatively rotatable part arranged to be turned from one limit position to another, the stationary part having diametrically opposed air inlet quadrants and the rotatable part having diametrically opposed closed quadrants arranged to cover the same when the rotatable part is in one limit position, the rotatable part having diametrically opposed series of air inlet openings on a given radius, and an adjustable 20 plate for each opening, said air inlet openings being arranged to be moved in succession into registration with the air inlet quadrants in the turning of the rotatable part toward the other limit position, the stationary part having the air inlet quadrants provided with diametrically opposed cut out portions constituting lateral extensions of the said quadrants, and the rotatable part having diametrically opposed secondary air inlet openings on a different radius from the aforesaid air inlet openings arranged to register with said cut out portions when the rotatable part is in the first mentioned limit position, and an adjustable plate 35 for each of the secondary openings.

4. In an air control shutter mechanism of the character described, the combination of a stationary shutter part and a relatively rotatable shutter part arranged to be turned from one limit position to another, said stationary part having diametrically opposed air inlet quadrants, and the rotatable part having diametrically opposed closed quadrants arranged to cover the same when the 45 rotatable part is in one limit position, the rotatable part having diametrically opposed series of air inlet openings on a given radius and an adjustable plate for each opening, said air inlet openings being so located as 50 to successively register with the air inlet quadrants in the turning of the rotatable part toward the other limit position, the succession alternating from one series to the other so that said plates are adjustable separately for one opening after another, the stationary part having the air inlet quadrants provided with diametrically opposed cut-out portions constituting lateral extensions of said quadrants, the rotatable part 55 having diametrically opposed secondary air inlet openings on a different radius from the aforesaid air inlet openings, both of which are in register with said cut out portions when the rotatable part is in the first mentioned limit position and are arranged to

simultaneously come into register with the air inlet quadrants proper in the turning of the rotatable part toward the other limit position, and an adjustable plate for each of the secondary openings.

In witness of the foregoing I affix my ⁷³ signature.

JOHN H. McILVAINE.
